UNITED STATES PATENT OFFICE.

EDWARD C. AHLHEIM, OF MANSFIELD, OHIO.

FLUSH-VALVE.

1,248,777.

Specification of Letters Patent.

Patented Dec. 4, 1917.

Application filed December 11, 1916. Serial No. 136,150.

To all whom it may concern:

Be it known that I, EDWARD C. AHLHEIM, a citizen of the United States of America, residing at Mansfield, in the county of Rich-
5 land and State of Ohio, have invented cer-
tain new and useful Improvements in Flush-
Valves, of which the following is a speci-
fication.

This invention relates to flush valves.

10 The present invention is designed as an improvement in Letters Patent No. 1,187,595 granted to me on the 20th day of June, 1916, and has the same objects in view generically.

15 The primary object of the present invention is to provide means of permitting and regulating the flow of water through a valve to a bowl or the like, and to arrange and locate the regulating means in such a manner as to permit it to be adjusted to allow 20 a predetermined flow of water therethrough from the exterior of the valve.

25 A further object is to provide simple, efficient and convenient means for flushing a bowl or the like, which results in saving of labor and expense in accomplishing the objects set out in the above described Letters Patent because of the elimination of a large number of parts which are necessarily used in the construction of the device described 30 in the above mentioned Letters Patent.

These and other objects are attained by the mechanism illustrated in the accompany-
35 ing drawing in which:

Figure 1 is a vertical central section of the invention showing it in its preferred em-
bodyment.

Fig. 2 is a horizontal section on the line O O of Fig. 1.

Fig. 3 is a top plan view of the invention.
40 The valve comprises a casing consisting of an upper section A and a lower section B fastened together in any well known manner. The upper section A of the casing is provided with vertical ribs c and d which 45 are preferably made integral with a circular member e which forms part of a valve chamber. The circular member is spaced apart from the casing. A cup shaped member g is threadably connected to the circular member e thereby increasing the length and 50 area of the chamber f.

Reference numeral 1 represents an inlet and 2 an outlet which permits the flow of water to a bowl or the like (not shown).
55 In the operation of the valve water is con-
ducted to the inlet 1 of the valve, but is

prevented from flowing through the valve mechanism to the bowl when the valve is in the closed position shown in Fig. 1 in full lines. When the valve is open water flows 60 through the passageway or port 3 filling up the chamber f and its extension 4, thereby exerting a pressure upon the main valve 5 forcing it to seat as shown in full line Fig. 1.

Pressure is also exerted upon a relief 65 valve 6 by the water thereby assisting the spring 7 to normally seat and close said relief valve. The above describes the opera-
tion and principles upon which the water exerts a pressure upon the valve mechanism 70 closing same under normal conditions. In the operation of the valve mechanism to per-
mit a predetermined quantity of water to pass through the valve to flush a bowl or the like, sufficient pressure is exerted upon the 75 push button 8 to counteract the tension of the spring 7, which in turn forces the relief valve 6 from its seat and the pressure of the water in the chamber f and extension 4 is then relieved as the water is permitted 80 to pass out of the chamber around the re-
duced portion of the stem 9 through the ports 10 and 11 to the casing, thence out through the outlet 2 to a bowl or the like.

A tubular main valve stem 12 is mov- 85 ably mounted in a boss 13 which is provided with an aperture to movably receive the stem 9. When the pressure of water in the chamber is relieved by the relief valve as described, further pressure is exerted upon 90 the push button 8 forcing the stem 9 to travel until the gland nut 12', which is at-
tached to the tubular stem is forced in contact with a lock nut 14 which is adjustably secured to the boss 13 of the valve casing. 95

This operation or manipulation is con-
tinued until the main valve is forced beyond the inlet 1 to its open position which is in-
dicated by dotted lines in Fig. 1 permitting 100 the water from the inlet to pass over the valve and out through the opening 16 pro-
vided in the circular member e into the cas-
ing; thence through outlet 2 to a bowl or the like. The quantity of water allowed to flow 105 through the valve to a bowl or the like is predetermined by the adjustment in either direction of the lock nuts 14 and 15, the nut 14 stopping the movement of the main valve stem, thereby permitting the main valve to close the passageway or port 3 more 110 or less to permit a predetermined quantity of water to flow through the valve. The

effect of reducing the flow of water through the passageway or port 3 into the chamber is to retard the closing of the main valve thereby giving more time and consequently increased flow of water from the inlet 1 through the valve before the main valve is closed by the pressure of water in the chamber.

When it is desired to decrease the flow of water through the valve after manipulation of the push button to impart movement thereto, the lock nuts are adjusted to stop the movement of the main valve so as to permit a larger area of the port 3 to remain in open communication with the chamber which has the effect of accelerating the closing of the valves on account of the increased pressure of the water.

Attention is called to the fact that convenience and ease of operation and adjustment of the mechanism to permit the flow of a predetermined amount of water through the valve is accomplished because all of the adjusting mechanism is arranged upon the exterior of the valve body which permits the adjustment thereof to stop the opening movement of the main valve at any point desired without disassembling any part of the said mechanism.

The push button 8 is counterbored to receive and nest the spring 7, said spring being constructed to project slightly from the face of the button to permit it to be constantly in contact with the gland nut 12' under compression. The stem 9 is made of such a length as to permit the button 8 which is attached thereto, to be maintained spaced apart from the gland nut as shown in Fig. 1, which permits the relief valve to be completely opened prior to the time that the gland nut 12' is forced in contact with the lock nut 14. The circular member e is cut away at 17-17 to permit an increased flow of water around the main valve at the inlet 1.

I claim:

1. In a flush valve, the combination of a casing, a valve chamber supported within the casing and open at its lower end, a member removably connected to the lower end of the valve chamber for forming a closure therefor, said casing having an inlet port therein for delivering a liquid to the valve chamber, and having also a passage forming a communication between the port and

valve chamber for continuously delivering liquid to the valve chamber, a valve in the valve chamber for closing the port, said valve being moved to closed position by the liquid entering the chamber through said passage, a hollow valve stem connected to the valve and in communication with the valve chamber, and provided with outlet ports, a stem slidably mounted in the hollow stem and constructed to permit liquid to pass from the valve chamber to the ports of the hollow stem, a relief valve on said stem and adapted to be seated on said main valve for closing the hollow stem, and a spring interposed between the ends of the stems for normally seating the relief valve, whereby the liquid entering the valve chamber through the passage may seat the main valve and close the main port.

2. In a flush valve, the combination of a casing, a valve chamber supported within the casing and open at its lower end, a member removably connected to the lower end of the valve chamber for forming a closure therefor, said casing having an inlet port therein for delivering a liquid to the valve chamber, and having also a passage forming a communication between the port and valve chamber for continuously delivering liquid to the valve chamber, a valve in the valve chamber for closing the port, said valve being moved to closed position by the liquid entering the chamber through said passage, a hollow valve stem connected to the valve and in communication with the valve chamber, and provided with outlet ports, a stem slidably mounted in the hollow stem and constructed to permit liquid to pass from the valve chamber to the ports of the hollow stem, a relief valve on said stem and adapted to be seated on said main valve for closing the hollow stem, a spring interposed between the ends of the stems for normally seating the relief valve, whereby the liquid entering the valve chamber through the passage may seat the main valve and close the main port, a gland nut on the hollow stem, and adjustable lock nuts on the casing adapted to be engaged by the gland nut for regulating the movement of the hollow stem and the opening of the inlet port.

In testimony whereof I affix my signature.

EDWARD C. AILHEIM.
